FREQUENCY CONTROLLED MECHANISM

Werner Koenig, Lucerne, Switzerland, assignor to
Landis & Gyr, A.-G., Zug, Switzerland, a corporation of Switzerland

Original application January 13, 1931, Serial No. 508,475. Divided and this application November 24, 1934, Serial No. 754,691. In Switzerland January 15, 1930

5 Claims. (Cl. 175—338)

This application is a division of my prior application Serial No. 508,475, filed January 13, 1931, patented March 12, 1935, Number 1,993,888.

The present invention relates to frequency controlled mechanism and more particularly to a novel and useful frequency controlled mechanism in which a rotating member is controlled and actuated by a frequency responsive member.

Objects and advantages of the invention will be set forth in part hereinafter and in part will be obvious herefrom, or may be learned by practice with the invention, the same being realized and attained by means of the instrumentalities and combinations pointed out in the appended 15 claims.

The invention consists in the novel parts, constructions, arrangements, combinations and improvements herein shown and described.

The accompanying drawing, referred to hereinafter and constituting a part hereof, illustrates one embodiment of the invention, and together with the description, serves to explain the principles of the invention.

The drawing shows a front elevation of one 25 illustrative embodiment of the present invention, certain parts being omitted.

The present invention has for its object the provision of a frequency controlled mechanism, suitable for use in connection with the operation 30 of switching mechanism, registers or recording mechanism. A further object is the provision of such a mechanism which is efficient and reliable in its operation and at the same time simple and of relatively inexpensive construction. Still another object is the provision of such a mechanism in which the parts need not be initially adjusted, and need not be adjusted from time to time to 35 compensate for wear.

In accordance with the present invention, a 40 resonant reed is provided, adapted to vibrate when subjected to a driving force of the proper frequency, and cooperates with a rotating member to intermittently rotate the member. As embodied, the rotating member is normally held 45 against rotation by means which are released only by resonant vibration of the vibratory member.

It will be understood that the foregoing general 50 description and the following detailed description as well, are exemplary and explanatory of the invention, but are not restrictive thereof.

Referring now in detail to the present preferred and illustrative embodiment of the present invention, a resonant spring member or reed 55 10 of resilient magnetic material is securely

mounted in a frame by means of the cross members 11, and its free end is positioned between the pole pieces 12 of a driving electromagnet 13, which may be supplied with a fluctuating or alternating electrical current of a predetermined frequency through the mains 14.

Cooperating with the resonant reed 10 is a rotatable member adapted to be rotated by vibration of the reed, but normally held against rotation and released only by vibration of the 10 reed at its resonant frequency. Reed 10 is associated with a rotatable shaft 15, to be driven and controlled by vibration of the reed, and shaft 15 carries a notched disc 16 which together with pin 17 carried by the pivoted pawl 19, serves 15 normally to prevent rotation of shaft 15. Pawl 19 is provided at its free end, with a downwardly extending nose 21 which rests on the reed 10 so that pawl 19 is raised releasing disc 16 on resonant vibration of reed 10. 20

Shaft 15 is rotatable in the bearings 22 and has a limited degree of horizontal movement, being pressed toward the free end of reed 10 by pivoted lever 24 and spring 25. For driving the shaft, in the direction of the arrow, reed 10 25 is provided with a laterally extending plate 30 and a smooth disc 31 is fixed on shaft 15 so that it is pressed against the plate 30 by spring 25. On vibration of the reed 10, plate 30 is similarly 30 vibrated and contacts with the periphery of the disc 31 on its downward movement.

On its upward movement, plate 30 is released from contact with the disc 31, due to the smaller mass and faster movement of the plate 30 under influence of reed 10, than the lateral movement 35 of discs 16 and 31 under spring 25.

Resonant vibration of the reed 10, first lifts pin 17 out of engagement with the notch 27 on disc 16, and at the same time slightly advances the discs 16 and 31 to move the notch 40 out of position to be engaged by the pin 17. On further vibration of the reed, plate 30 intermittently advances the discs 16 and 31 and shaft 15 until the pin 17 again drops in one of the notches. 45

The invention in its broader aspects is not limited to the specific mechanisms shown and described but departures may be made therefrom within the scope of the accompanying claims without departing from the principles of the invention and without sacrificing its chief advantages. 50

What I claim is:—

1. Frequency controlled mechanism including in combination a laterally movable, rotatable disc, 55

a vibratable reed, means for vibrating the reed, a disc-engaging member carried by the reed and means for yieldingly moving the disc into engagement with the member.

- 5 2. Frequently controlled mechanism including in combination a laterally movable, rotatable disc, a vibratable reed, means for vibrating the reed, a disc-engaging member carried by and vibrating with the reed, means for yieldingly moving the disc into engagement with the member, and means for preventing rotation of the disc except on resonant vibration of the reed.
- 10 3. Frequency controlled mechanism including in combination a laterally movable, rotatable disc, a vibratable reed, an electromagnet for vibrating the reed, a disc-engaging member carried by and vibrating with the reed, means for yieldingly moving the disc into driving engagement with the member, a notched disc fixed relatively 15 to the rotatable disc, and a pin engaging with

said notched disc to prevent rotation of the disc, said pin being released only by resonant vibration of the reed.

4. Frequency controlled mechanism including in combination a rotatable disc mounted on a movable axis, a vibratable reed, means for vibrating the reed, a disc-engaging member carried by the reed and means for yieldingly moving the disc into engagement with the member to rotate the disc. 10

5. Frequency controlled mechanism including a vibratable reed, means for vibrating the reed, a rotatable disc mounted on a movable axis, a second rotatable disc fixed relatively to said first disc, a disc engaging member carried by 15 said reed and means for yieldingly pressing the first disc into engagement with said disc engaging member.
